CLAIM

The ornamental design for a combined lamp and bracket, as shown and described.

DESCRIPTION

FIG. 1 is a perspective view of a combined lamp and bracket of my new design, with the broken line showing for illustrative purposes only and forming no part of the claimed design;

FIG. 2 is a front elevation of a combined lamp and bracket shown in FIG. 1;

FIG. 3 is a rear elevation of a combined lamp and bracket shown in FIG. 1;

FIG. 4 is a top plan view of a combined lamp and bracket shown in FIG. 1;

FIG. 5 is a bottom plan view of a combined lamp and bracket shown in FIG. 1;

FIG. 6 is a left side elevation of a combined lamp and bracket shown in FIG. 1; and

FIG. 7 is a right side elevation of a combined lamp and bracket shown in FIG. 1.
